SHIPPING CONTAINER

Herman H. Strauss, St. Louis, Mo., assignor to
 Gaylord Container Corporation, St. Louis, Mo.,
 a corporation of Maryland

Application April 1, 1949, Serial No. 84,997

2 Claims. (Cl. 229—5.5)

1

This invention relates to heavy duty shipping containers, particularly folded-blank or cartons of the kind comprising a multi-sided tubular body and a separate end closure disc fitting in one or each end of said tubular body and supported and/or retained therein by internal hollow ledge sections formed by inwardly folded marginal flaps of the side wall panels thereof.

The principal object of the present invention is to provide for automatically and irreversibly locking said hollow ledge sections together at their adjacent ends to form a continuous hollow inner peripheral supporting and/or retaining ledge for the end closure. Another object is to provide a continuous hollow ledge having a cross-sectional shape which will greatly increase the strength and rigidity of the ledge and the carton. Another object is to shape and arrange the folded ledge forming sections so that they cannot be unfolded without damaging or destroying the carton.

According to the present invention, the side wall panel flaps at one or each end of the carton are folded inwardly along the three spaced parallel score lines into said end of said carton to form on the inner sides of said panels hollow ledge sections of substantially right-angled triangular cross-section, with the two right angularly disposed sides of the triangle positioned one flatwise against said panels and the other normal thereto and facing inwardly away from said end of said carton and with the third side or hypotenuse of the triangle facing outwardly towards said end. The flaps are shaped so that the hollow right-angled triangular ledge sections formed thereby are automatically and irreversibly interlocked one with the other at their adjacent ends to form a rigid, continuous inner peripheral ledge for stiffening and strengthening the carton and supporting and/or retaining the end closure therein. The invention is applicable to containers of various types and of square, rectangular, triangular or polygon shape.

The invention is more fully explained by reference to the accompanying drawings, which form part of this specification and wherein like symbols refer to like parts wherever they occur.

Fig. 1 is a perspective view of a shipping container embodying my invention,

Fig. 2 is a top plan view of said container,

Fig. 3 is a vertical section on the line 3—3 in Fig. 1.

Fig. 4 is an enlarged fragmentary vertical section through the upper end portion of the container at one side thereof,

2

Fig. 5 is a horizontal section on the line 5—5 in Fig. 4,

Fig. 6 is a vertical sectional view of the upper portion of the container, showing the manner of folding of the closure retaining flaps therein,

Fig. 7 is a plan view of the blank from which the tubular body of the container is formed,

Fig. 8 is an enlarged fragmentary plan view of the blank, showing the notched ends of adjacent closure retaining flaps,

Fig. 9 is a fragmentary end view of the carton, showing the portion of the last flap before it is snapped between the finally positioned flaps at opposite ends thereof not shown.

15 Fig. 10 is a perspective view of a container of polygonal form constructed in accordance with my invention,

Fig. 11 is a top plan view of the modified container shown in Fig. 10,

Fig. 12 is an enlarged vertical sectional view on the line 12—12 in Fig. 10,

Fig. 13 is a fragmentary horizontal sectional view on line 13—13 in Fig. 12,

20 Fig. 14 is a plan view of the blank from which the tubular body of the modified form of container is formed,

Fig. 15 is an enlarged fragmentary plan view of the blank shown in Fig. 13, showing the notched ends of adjacent closure retaining flaps; and

Fig. 16 is a fragmentary end view of the modified carton, showing the position of the last flap before it is snapped between the finally positioned flaps at opposite ends thereof.

25 In Figs. 1 to 9, inclusive, of the accompanying drawings my invention is shown embodied in the heavy duty shipping container comprising a multi-sided tubular open-ended body A and an end closure disc B fitting therein adjacent to each end thereof, said tubular body and end closures being preferably made of corrugated board, fiberboard, or like material. The tubular body of the container or carton is divided by vertical creases or scores 1 into four side wall panels 2 and is made from a flat blank having a flap 3 at one end that overlaps and is permanently secured by staples 4 or tape to the opposite end of said blank at one vertical corner of said tubular corner.

30 Each side wall panel 2 is provided with upper and lower marginal flaps 5 that are each divided by three spaced parallel horizontal score lines 6, 6a and 6b, respectively, into an inner marginal panel 7, an intermediate panel 8 and an outer marginal panel 9. As shown in Fig. 7, a V-

shaped notch 10 is formed in each end of each of the upper and lower marginal flaps 5 of each side wall panel 2. One side of each V-shaped notch 10 extends from the score line 6 to the score line 6a, thereby providing the inner marginal panel 7 with an oblique-angled end 11; and the other side of said notch extends from the score line 6a to the score line 6b, thereby providing the intermediate panel 8 with an oblique-angled end 12. The outer marginal panel 9 of the flaps 5 is provided with square or right-angled ends 13.

The flaps 5 at each end of the tubular body A of the container or carton are each bent progressively inwardly into said end along the score lines 6, 6a and 6b to form a hollow horizontally disposed ledge section C of substantially right-angled triangular cross-section on the inside face of the side wall panel 2 which carries said flap. In this folded ledge forming position of each flap 5, the panels 8 and 9 thereof form the two right angularly disposed sides of the rib section C, while the panel 7 forms the hypotenuse or inclined third side thereof. As shown in the drawings, the ledge section C is positioned with the panel 8 seated flatwise against the corresponding side wall panel 2 of the carton, with the panel 8 disposed horizontally or extending normal to said side panel and facing inwardly away from the adjacent end of said carton, and with the inclined panel 7 facing outwardly toward said end. The vertical panel 9 of the hollow right-angled triangular ledge section C is positioned with its upper edge snugly seated in the vertex of the acute angle formed by the inclined panel 7 of said ledge section and the corresponding side wall panel 2 of the carton.

The score lines 6, 6a and 6b of each of the flaps 5 are spaced so that the hollow right-angled triangular ledge section C formed by the folded flap has its inwardly inclined outwardly facing panel 7 disposed at an acute angle of approximately 42° to panel 9 positioned flatwise against side wall panel 2. The oblique-angled ends 11 of the inwardly inclined outwardly facing panels 7 of adjacent hollow triangular ledge sections C are inclined at an angle that will bring said ends into conterminous endwise abutting relation. The oblique-angled ends 12 of the inwardly facing panels 8 of adjacent ledge sections are also inclined at an angle that will bring said ends into conterminous endwise abutting relation. The square or right-angled ends 13 of the vertical panels of the adjacent hollow triangular ledge sections C are also disposed in conterminous endwise abutting relation. By this arrangement the ledge sections C are rigidly irreversibly interlocked in end to end relation in the end of the tubular body A of the carton to form therein a continuous internal peripheral ledge of hollow right-angled triangular cross-section. The upper and lower end closure disks B snugly fit within the tubular body A of the carton inwardly of the continuous hollow right-angled ledges at said ends, the lowermost end closure disk seating on the horizontal panel 8 of the lower ledge, while the uppermost end closure disk is supported on the contents of the carton with its marginal portion overlapped by and in position to seat flatwise against the horizontal panel 8 of the uppermost ledge.

In forming the continuous internal peripheral hollow right-angled triangular ledge in each end of the tubular body A of the carton, one marginal

flap 5 at said end is first folded along the score lines 6a and 6b to form the hollow right-angled triangular ledge section, after which said flap is folded along the score line 6 to bring said section into its final position in the end of the carton. The next adjacent flap 5 is then folded in a similar manner along its score lines 6a and 6b thereof to form the ledge section which will extend over the adjacent end of the first ledge section. This second flap is then folded inwardly along its score line 6 to cause the ledge section thereof to snap or spring over the adjacent end of the finally positioned first ledge section with the adjacent ends of the two finally positioned rib sections in conterminous endwise abutting relation. The remaining flaps are folded and snapped into final position in a similar manner. The last flap, however, when folded along the score lines 6a and 6b to form the triangular rib section overlaps the ends of the adjacent finally positioned ledge sections at opposite ends thereof, and this last ledge section when folded inwardly at score line 6 into its final position snaps over the ends of the finally positioned ledge section at opposite ends thereof, thus completing the continuous internal peripheral hollow right-angled triangular ledge and irreversibly locking all of the ledge forming sections together as a result of the abutting joints between the ends of the panels 7, 8 and 9 of adjacent rib section.

In the modification shown in Figs. 10 to 16, inclusive, the tubular body of the carton is of polygonal shape and the six side wall panels 2a have upper and lower marginal flaps 5a that are similar to and are folded along score lines 6, 6a and 6b in the same manner as the marginal flaps 5 of the hereinbefore described four-sided carton to form hollow right-angled triangular ledge forming ribs C' of the same cross-sectional shape and size as the ledge forming ribs C of the four-sided carton. In this six-sided carton construction, the V-shaped notches 10a with ends of the flaps 5a have their sides disposed at the particular angles required to provide the panels 7 with oblique-angled ends 11a and the panels 8 with oblique-angled ends 12a so that the ends of the panels 7 of adjacent ledge forming sections C' and the ends of the panels 8 thereof are brought into conterminous endwise abutting relation to form wedge joints for locking the ledge sections together to form a continuous internal ledge of hollow right-angled triangular section.

Within the limits of the tensile strength of the bendable material of which the carton is constructed, increased weight of lading more effectually interlocks the hollow ledge sections into a continuous irreversible support and/or retainer for the end closures of the carton. Substantially equal distribution of the weight of the lading between the supporting legs of the triangular ledge sections and maximum strength thereof is attained when the acute angle opposite the horizontal side of the right triangular cross-section is approximately 42°. While this angle may be varied within reasonable limits, increasing or decreasing the angle tends to unequally distribute the weight between the supporting elements with corresponding impairment of rib strength. The right triangular cross-sectional shape of the ledge elements with the acute angle of approximately 42° opposite the horizontal side is common to all polygonal receptacles regardless of size.

The described right triangular ledge section with the lesser acute angle of about 42° results from a specific spacing of the score lines on the

marginal flaps along which the flaps are progressively folded. The scores 6, 6a and 6b are spaced apart in the ratio of approximately 1.4995, 1.1106, 1.000, respectively, measured on the median plane of the paperboard or other bendable material. As an example of the practical application of the scoring principle, on receptacles of a diameter up to the order of 15", constructed of paperboard $\frac{1}{8}$ " in thickness, the width of the panel 7 may be $1\frac{3}{4}$ ", the width of the panel 8 may be $1\frac{1}{8}$ ", and the width of the panel 9 may be 1".

The mechanical interlocking feature of the ledge sections results from the novel angular construction of the scored marginal flaps. Each fold of the flaps is slotted or slit and cut out in such manner that when the flap is folded into its ultimate position with respect to the side wall panel, the plane of the end of each side of each right triangular hollow ledge section thus formed will be in conterminous end abutment with the corresponding side of the contiguous ledge section.

The angular cutouts and slots or slits in the marginal flaps are constant for all square, hexagonal or all polygonal type receptacles regardless of variations in diameter or size of panels within each class. The novel geometric design of the cutouts is arrived at by (1) slotting or slitting the marginal flaps vertically along the median plane of the side wall score lines 1 to the intersection of the median plane of flap score 6b, (2) determining the angle of the cutting line which is to extend from the flap score 6b to the flap score 6a. This angle is derived from the formula—

$$180^\circ - \frac{360^\circ}{N}$$

2

in which N is the number of side walls of the receptacle. This cut is carried from the intersection of the median planes of the vertical slot or slit and the flap score 6b to the median plane of the flap score 6a, thence to the intersection of the median planes of the flap score 6 and the vertical side panel score 1.

This cutout with the corresponding reversed cutout of the contiguous flap invariably forms two isosceles triangles having a common base along the median line of the second score, irrespective of the number of sides of the receptacle. To illustrate, the cutting line for a square or rectangular receptacle, will be—

$$180^\circ - \frac{360^\circ}{4}$$

2

The isosceles triangle formed by the cutout between the score lines 6a and 6b of contiguous flaps will have base angles of approximately 45° and an apex angle of approximately 90° , while the corresponding isosceles triangle between the score lines 6 and 6a, will have base angles of approximately 54° and an apex angle of approximately 72° .

For a hexagonal shaped receptacle, the cutting line will be—

$$180^\circ - \frac{360^\circ}{6}$$

2

The base angle of the triangle between the scores 6a and 6b will be approximately 60° and the apex angle approximately 60° while the base angle of

the triangle between the scores 6 and 6a will be approximately 66.5° and the apex angle approximately 47° .

This geometric cutout design results in the conterminous end abutment of each fold of each marginal flap with the corresponding fold of the contiguous marginal flap when said flaps are folded into their final position, and is an essential feature of the invention.

The novelty, therefore, of the invention comprises the construction and assembly of the folds of the marginal flaps of the container, which in their ultimate position form a continuous hollow rib of right triangular cross section in combination and in cooperation with the design of cutouts and slots or slits in said flaps whereby upon folding each rib section into its described triangular form, it rests upon and projects over the two adjacent folded flaps by a substantial margin and may be snapped into its final place, completing the continuous hollow supporting peripheral rib and automatically and irreversibly locking all of said rib elements securely in place.

The hereinbefore described carton construction has several important advantages. It provides a strong and durable pilferproof and substantially sift-proof carton of simple and economical construction for packaging a wide variety of materials or articles. The body flaps may be quickly and easily folded and automatically and irreversibly locked together to form strong and rigid continuous hollow end closure retaining and/or supporting ledges for the end closure disks. The right-angled triangular cross-sectional shape of the ledges greatly increases the strength and rigidity thereof; and the beveled ends of adjacent end and intermediate panels of the triangularly folded ledge forming flaps match together perfectly along lines bisecting the angle 40 of junction thereof to form wedge or miter joints which prevent the flaps from being unfolded without destroying or damaging them. The invention is applicable to cartons of square, rectangular, triangular or polygonal shape merely by varying the angularity of the sides of the V-shaped notches in the ends of the ledge forming flaps. The size of the hollow right-angled triangular cross-section of the ledges may be varied by varying the width and score line spacing 45 of the ledge forming flaps. The angularity of the sides of the V-shaped notches remains constant for a carton having a given number of sides regardless of the diameter of the carton.

If desired, the top and bottom closure of the 50 carton may be glued to the hollow inner peripheral right triangular cross-sectional supporting ledge to provide a completely siftproof package. These top and bottom closures may be made of wood, metal or suitable material to provide increased strength where required and desired.

What I claim is:

1. A shipping container comprising a tubular body having a plurality of connected together side wall panels, an extension of each panel constituting a similar hollow ledge section polygonal in cross section consisting of connected together panels with one panel thereof folded in face-contacting relation to the body panel of which it is an extension, the said one panel constituting the outer wall of said hollow ledge section, the said ledge sections being disposed inwardly of the body at one end thereof to form a continuous ledge for an end closure, the opposite unconnected ends of each ledge section having a vertical edge on said one panel facing an adjacent

body panel at the interior junctures of the connected body panels and having the remaining ledge panels with their edges extending angularly inwardly away from the body panels, the adjacent panel ends of the ledge sections forming a fixed miter point at the junctures of the body and ledge panels with the said vertical edges and the said angularly inwardly extending edges in contacting relationship; and the said contacting edges solely forming the said fixed joint for preventing displacement of any one or all of the ledge sections relative to each other and to the body.

2. A shipping container comprising a tubular body having a plurality of connected together side wall panels, an extension of each panel constituting a similar hollow ledge section triangular in cross section consisting of three connected together panels with one panel thereof folded in face-contacting relation to the body panel of which it is an extension, the said one panel constituting the outer wall of said hollow ledge section, the said ledge sections being disposed inwardly of the body at one end thereof to form a continuous ledge for an end closure, the opposite unconnected ends of each ledge section having a vertical edge on said one panel facing an

adjacent body panel at the interior junctures of the connected body panels and having the remaining ledge panels with their edges extending angularly inwardly away from the body panels, the adjacent panel ends of the ledge sections forming a fixed miter joint at the junctures of the body and ledge panels with the said vertical edges and the said angularly inwardly extending edges in contacting relationship and the said contacting edges solely forming the said fixed joint for preventing displacement of any one or all of the ledge sections relative to each other and to the body.
